UNITED STATES PATENT OFFICE.

ADOLPH M. HOLSTEIN, OF SYRACUSE, NEW YORK.

DESIGN FOR A CORNER-PIECE FOR COFFINS AND CASKETS.

46,827.

Specification for Design.

Patented Jan. 5, 1915.

Application filed September 11, 1914. Serial No. 861,313. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Corner-Piece for Coffins and Caskets, of which the following is a specification, reference being had to the accompanying drawing, forming a part hereof.

In the drawing, Figures 1, 2 and 3 are, respectively, side and front elevations and top plan view of my design for a corner piece for coffins and caskets.

This design of corner piece for coffins comprises angularly arranged faces, and embossed figures running lengthwise of said faces, the embossing consisting of a central lengthwise elongated rotund figure or ridge 1 and similar ridges 2 on opposite sides of the central ridge. The ridges 1, 2, viewed from the top, as shown in Fig. 3, have the appearance of three lobes, and viewed in face view, bulge or swell at their lower

ends, contract upwardly toward the central portion of the corner piece, again bulge into a spherical form at 3, and then contract again and swell at the top of the corner piece. Said ridges are capped by hoods 4 which droop downwardly at their margins and have a greater droop over the central or highest points of the ridges. The surfaces at the lower ends of the ridges recede in abrupt curves at 5 to the extreme lower end of the corner piece.

I claim:

The ornamental design for a corner piece for coffins and caskets, substantially as shown and described.

In testimony whereof, I have hereunto signed my name in the presence of two attesting witnesses, at Syracuse, in the county of Onondaga, and State of New York, this 5th day of September, 1914.

ADOLPH M. HOLSTEIN.

Witnesses:

S. DAVIS,
F. B. PICKARD.
